SELECTIVE COMBINATION SALT-AND-PEPPER SHAKER

Wesley Sandford, Berkeley, Calif.

Application December 18, 1950, Serial No. 201,436

5 Claims. (Cl. 222—42)

1

This invention relates to improvements in salt and pepper dispensers and provides a unitary shaker for selectively or simultaneously dispensing either or both, salt and pepper, and when dispensing both, they can be dispensed in any desired proportion. This invention also provides means for identifying the seasoning which will be dispensed, and when both are simultaneously dispensed, indicate the relative proportions. The two seasonings are completely and effectively sealed from each other and cannot become intermixed within the container, because of an effective locking arrangement for the cover which permits rotation of the cover without varying the relative axial position, the cover remaining in the same plane for all adjustments. Obviously the same arrangement can be used for several different seasonings by providing additional partitions with the cover arranged with dispensing apertures to include only a single compartment.

This device is simple and easy to manufacture, particularly of thermo-plastic materials, as all parts are made to draw easily from molds, and therefore can be made to sell at a very reasonable price, and obviously, will be more convenient for use since only one dispenser is required eliminating the frequent searches and inspections when either of the seasonings is desired, and additionally reducing the number of pieces required in setting a table.

It is known that combination salt and pepper shakers have been made, but these usually are of the type in which the device is turned bodily to dispense either, the salt or the pepper, both sides having dispensing apertures, with no perfect seals between the respective compartments.

Applicant's dispenser always maintains a perfect seal between the compartments and is adjustable to dispense any one of the seasonings alone or any proportion of two seasonings, merely by adjusting the cap which has dispensing apertures which include an area less than the area of any one compartment.

The objects and advantages of the invention are as follows:

First, to provide a combination seasoning dispenser which is adjustable to dispense a single seasoning only, or a combination of two seasonings in any desired proportions simultaneously.

Second, to provide a dispenser as outlined with a cap having dispensing apertures formed within an area less than the area of any compartment.

Third, to provide a dispenser as outlined in which perfect seals are maintained between the compartments under all adjustments so as to prevent admixture of seasonings.

2

Fourth, to provide a new type of cover maintaining and retaining or locking means which does not alter the relative axial position of the dispensing cover irrespective of adjustments but which permits removal of the cover when desired.

Fifth, to provide a dispenser as outlined with indicating means for indicating the seasoning to be dispensed and additional indicating means for indicating the relative proportions of two seasonings to be dispensed simultaneously.

Sixth, to provide a dispenser as outlined which is simple and economical to manufacture and therefore capable of marketing at a very reasonable price.

In describing the invention reference will be had to the accompanying drawings, in which:

Fig. 1 is a vertical section through the invention.

Fig. 2 is a top plan view of Fig. 1.

Fig. 3 is a bottom plan view of the indicating plate and compartment seal.

Fig. 4 is a top plan view of the indicating plate and compartment seal including the stop means for limiting the relative rotative movement of the dispensing cover.

Fig. 5 is an enlarged view of the inside of the skirt of the dispensing cover showing the locking and retaining means.

The invention includes a receptacle 10 which may have any desired form, and includes a base 11 and a partition 12 which divides the container into a plurality of compartments.

The upper end of this container has an annular ring 13 spaced from the top 14 of the external wall, and has oppositely located projections 15 and 16 spaced slightly below the top 14, and the top 17 of the partition 12 is preferably formed to the same shape as the underside 18 of the cover 19 and terminates on each side coincident with the top 14 of the side walls of the container, and this partition is preferably provided with a central pivot 20 to insure proper centering of the indicator plate 21 which has depending ears 22 and 23 which span the thickness of the partition and maintain the plate against turning about the axis 20.

The dispensing cover slidably fits the upper end of the side walls as indicated at 24 and has a continuous groove 25 formed on the inside in which the projections 16 ride when the bottom edge 26 of the cover slidably engages the top surface 27 of the annular ring 13, and the distance from the top 27 of this annular ring 13 to the top 14 of the side wall and through the indicator plate is equal to the inside height of the cover skirt, thus

completing the seal between the partition and the cover.

This cover has a depending stop member 28 which selectively engages the walls 29 and 30 of the recesses 31 and 32 which are formed in the top of the indicator plate, the remaining portions 33 and 34 cooperating with the inside of the cover and thus maintaining the seal between the compartments.

The locking means consists of a groove 35 formed at an angle to the continuous groove 25 and continuing into a groove 36 parallel to the groove 25, and terminating in another groove 37 which opens through the bottom edge of the cover skirt.

The indicating means consists of a transparent frame 38 which is formed in one side of the top and through which the indicia 39 and 40 can be seen selectively. If plastic is used for molding the cover, a small section of the transparent plastic can be located in the mold and the main body of plastic can then be formed around it, or the opening can be made and the transparent section forced or otherwise secured in the opening. However it is important that the transparent section be flush with the underside of the cover.

The principal reasons for using a separate indicator plate and seal is that this indicator plate can be installed to suit the specific materials to be dispensed, as it can also be used for other seasonings, for chemicals and powders, and, because it greatly simplifies the molding of the container and therefor the cost of manufacture, since if this plate were molded in place with the partition, either the partition would necessarily be unduly thick, or a difficult coring job would result.

The dispensing apertures 41 cover an area less than the area of one of the compartments, and as shown in Fig. 2, the salt would be completely sealed in the container and only the pepper could be dispensed. By rotating the cover through 180 degrees until the stop 28 engages the other wall 29 as indicated in Fig. 4, the indicia "salt" will appear through the window 38 and the dispensing apertures 41 will be on the opposite side from that shown in Fig. 2. To equally dispense both seasonings, the cover is rotated until the two indicators 42 on the cover and 43 on the annular ring are brought into registry when the dispensing apertures will straddle the indicating plate and partition, and from that point the relative proportions dispensed are indicated by the amount these two indicators are out of registry. These indicators also serve as locators for the locking means. When they are in registry, the cover can be raised until the lugs 15 and 16 engage the bottom wall 44 of the slot 36, after which the cover must be rotated through a slight angle until stopped by the wall 45 of the slot 37, after which the cover can be removed. With the cover removed, the indicator plate can be changed to any other indicia as desired.

Thus, a dispenser is provided with which a plurality of different powdered and fine granular materials can be selectively dispensed or simultaneously dispensed in similar or different proportions, while maintaining an effective seal between the different materials irrespective of the adjustments of the dispensing means, and with the dispensing cover provided with retaining means for rotation of the cover in a constant plane, and with the cover removable only when in one relative rotative position coupled with rotation to a second position, and with the one

position suitably identifiable and with that identifiable position indicating simultaneously the position for equal dispensing of two materials simultaneously.

I claim:

1. A dispenser for powdered or fine granular materials comprising a container divided into compartments by an intervening partition, and a cover rotatable to two positions on the upper end of said container and having dispensing apertures formed within an area less than the area of either compartment for selective dispensing from the respective compartments, and with the compartments sealed from each other throughout their extent; means for maintaining said cover in the same plane during rotation thereof to said two positions and including locking means for retaining said cover against removal comprising a skirt on said cover slidably fitting the top of said container, projections on the upper end of the external walls of said container, and a continuous groove formed in the inside of said skirt with said projections riding therein, and a first depending groove connecting with said continuous groove and located midway between said two positions and terminating in a parallel groove similarly terminating in a second depending groove, and indicators on said container and said cover for indicating the registry of said projection with said first depending groove, whereby said cover is only partly withdrawable when the indicators are in registry, and the cover is removable only by a second rotative movement followed by withdrawal of the cover.

2. A salt and pepper shaker comprising; a container having a central vertical partition forming two compartments, a cover rotatable on the upper end of said container and having dispensing apertures formed in one half thereof with the other half forming a complete seal, whereby when the cover is in one position, dispensing occurs from one compartment, and when the cover is rotated to a second position dispensing occurs from the other compartment, and when the cover is rotated to any intermediate position dispensing occurs simultaneously from both compartments in proportion to the degree of over or under rotation relative to the partition; said container having an annular shoulder in spaced relation to the top of the external walls, and oppositely projecting lugs intermediate the height of the wall above said ring, said cover having a skirt, and an annular groove formed in the interior surface of said skirt and cooperating with said lugs, and outlet grooves communicating with said annular groove for removal of the cover when the outlet grooves are in registry with said lugs, for maintaining the cover in a constant relative plane for maintaining the seal between the cover and the partition.

3. A salt and pepper shaker comprising; a container having a central vertical partition forming two compartments, a cover rotatable on the upper end of said container and having dispensing apertures formed in one half thereof with the other half forming a complete seal, whereby when the cover is in one position, dispensing occurs from one compartment, and when the cover is rotated to a second position dispensing occurs from the other compartment, and when the cover is rotated to any intermediate position dispensing occurs simultaneously from both compartments in proportion to the degree of over or under rotation relative to the partition; oppositely projecting lugs formed on the upper portion of the

outside walls of said container; said cover having a depending skirt and an annular groove formed in the inside wall of said depending skirt and cooperating slidably with said lugs, opposite depending grooves formed in communication with said annular groove and terminating in grooves parallel to said annular groove and in turn terminating in exit grooves, and indicators formed respectively on said container and said skirt for indicating registry of said depending grooves with said lugs for partial removal of the cover, and being fully removable through a slight angular rotation of the cover for registry of the lugs with the exit grooves, said indicators simultaneously indicating the midposition of said cover for simultaneously indicating the midposition of said cover for simultaneous dispensing from both compartments in equal proportions with slight rotation in either direction varying said proportions at will.

4. A salt and pepper shaker comprising; a container having a central vertical partition forming two compartments, a cover rotatable on the upper end of said container and having dispensing apertures formed in one half thereof with the other half forming a complete seal, whereby when the cover is in one position, dispensing occurs from one compartment, and when the cover is rotated to a second position dispensing occurs from the other compartment, and when the cover is rotated to any intermediate position dispensing occurs simultaneously from both compartments in proportion to the degree of over or under rotation relative to the partition; said container having an annular shoulder in spaced relation to the top of the external walls, and oppositely projecting lugs intermediate the height of the wall above said ring, said cover having a skirt, and an annular groove formed in the interior surface of said skirt and cooperating with said lugs, and outlet grooves communicating with said annular groove for removal of the cover when the outlet grooves are in registry with said lugs, for maintaining the cover in a constant relative plane for maintaining the seal between the cover and the partition, an interchangeable indicating plate mounted on said partition and cooperating with the inside of said cover and forming sealing means between the partition and the cover irrespective of the rotative position of the cover, indicia formed on said plate, and a window in said cover for indicating the material to be dispensed when the cover is in its respective position.

5. A salt and pepper shaker comprising; a container having a central vertical partition forming two compartments, a cover rotatable on the upper end of said container and having dispensing apertures formed in one half thereof with the other half forming a complete seal, whereby when the cover is in one position, dispensing occurs from one compartment, and when the cover is rotated to a second position dispensing occurs from the other compartment, and when the cover is rotated to any intermediate position dispensing occurs simultaneously from both compartments in proportion to the degree of over or under rotation relative to the partition; an interchangeable indicating plate mounted on said partition and cooperating with the inside of said cover and forming sealing means between the partition and the cover irrespective of the rotative position of the cover, indicia formed on said plate, and a window in said cover for indicating the material to be dispensed when the cover is in its respective positions, oppositely projecting lugs formed on the upper portion of the outside walls of said container; said cover having a depending skirt and an annular groove formed in the inside wall of said depending skirt and cooperating slidably with said lugs, opposite depending grooves formed in communication with said annular groove and terminating in grooves parallel to said annular groove and in turn terminating in exit grooves, and indicators formed respectively on said container and said skirt for indicating registry of said depending grooves with said lugs for partial removal of the cover, and being fully removable through a slight angular rotation of the cover for registry of the lugs with the exit grooves, said indicators simultaneously indicating the midposition of said cover for simultaneous dispensing from both compartments in equal proportions, with slight rotation in either direction varying said proportions at will.
